UNITED STATES PATENT OFFICE.

FRANK DANIELSON, OF CHICAGO, ILLINOIS.

SPARK-PLUG.

1,286,244.

Specification of Letters Patent.

Patented Dec. 3, 1918.

Application filed August 19, 1916. Serial No. 115,845.

To all whom it may concern:

Be it known that I, FRANK DANIELSON, a citizen of the United States, residing at Chicago, in the county of Cook and State 5 of Illinois, have invented new and useful Improvements in Spark-Plugs, of which the following is a full, clear, and exact description.

My invention relates to spark plugs for 10 explosive engines, and particularly to that type of tubular metallic spark plugs having an electrode depending from its inner annular edge, and having another electrode depending from an insulated core extending 15 axially in said plug. Heretofore these electrodes have been so constructed that they were incapable of retaining gasolene, and priming was accomplished by injecting the gasolene directly into the cylinder in such 20 manner that the electrodes were simply exteriorly moistened or not affected by the injection at all.

One of the conditions that contributes to the effectiveness of spark-plugs now in extensive use in explosive engines is the incandescence of the electrodes. This requires the presence of gaseous vapors at the point where the spark passes from electrode to electrode, and the consequent ignition thereof. The common form of spark-plug, however, is so constructed that its lower end is open and solid carbon forms in this opening and materially affects its usefulness.

One of the objects of my invention is to 25 provide as large an incandescent electrode as possible and to prevent the accumulation of carbon in the lower end of the plug. Another object is to provide means for priming the plug and enable it to hold the initial 30 charge of explosive fluid where it can be readily ignited to start the engine and retain a sufficient quantity thereof where it will vaporize as the electrode becomes heated and enrich the explosive gas at the point 35 where the ignition takes place during the initial explosions of the engine. These and other objects I accomplish by the means hereinafter fully described, and as more particularly pointed out in the claims, reference being had to the accompanying drawings forming a part of this specification, in which—

Figure 1 is a side elevation of my improved spark-plug.

Fig. 2 is a vertical central section of the same.

Referring more particularly to Fig. 2 of the drawings, it will be observed that this priming plug consists of a substantially hollow cylindrical metallic retainer or plug 1. The lower portion of this retainer is exteriorly screw-threaded and is adapted to be screwed into a suitable opening in the cylinder of a gas engine, and its lower annular edge is provided with oppositely disposed electrodes 2, 2, consisting, preferably, of short downwardly extending straight wires, the upper end of each of which is anchored in the metal of the plug and the lower end terminates a short distance below the same. The upper end of the bore of this retaining member or plug is, preferably, increased in diameter, and a body or barrel 3 of porcelain, mica, stone, or other suitable insulating material, is inserted 75 therein.

At a point just below its center of length, this porcelain body is increased in diameter and the shoulder 6 at the lower end of this widened portion is seated on a shoulder 80 made by increasing the upper portion of the bore of the plug, as hereinbefore stated, and said body is locked in this position in the plug by a suitable gland-nut 7 that screws into the upper end of the same and engages the interior screw-threads thereof. The upper end of the porcelain body is protected by a cap 4 which has a downwardly extending annular flange which is seated in the rabbeted upper edge of said body.

Body 3 has a longitudinal bore extending therethrough the lower portion of which (commencing at a point within the widest portion of the plug) is wider than the upper portion thereof. A tubular metallic electrode 8 is inserted through the said bore which is of such length that its ends extend beyond the ends of the body, and is of such diameter that its upper portion contacts with the walls of said bore while its lower portion is separated therefrom. Just below the point where the bore of the body is increased in diameter, the electrode is expanded in any suitable manner to form a boss 9 and cap 4 is screwed onto the upper screw-threaded portion of the same to clamp it in the body between said boss and cap and to immovably secure it in its proper assembled position. Electrode 8 extends down below the lower ends of both the body and plug 1, and a short distance below the latter has an inverted mushroom-shaped

head 10 removably secured thereto by means of a screw 11, which screws up into the lower end of the bore of the electrode and closes the lower end thereof. Head 10 5 may be made integral with the lower end of the electrode, if desired, but I prefer to make it removable so that, when oxidation wears away its edge opposite electrodes 2, 2, the screw can be loosened and the head 10 turned until an unaffected portion of the edge thereof is opposite said electrodes 2, 2, and the proper distance between the two electrodes is re-established, or a new head substituted therefor. The diameter of this 15 head is, preferably, slightly less than the lower end of the bore of plug 1, and its upper side is concaved and its under side convexed, substantially as shown in the drawings.

20 Just below boss 7 and well up in the lower wider portion of the bore of the body, electrode 8 is provided with one or more perforations 12, so that when gasolene is poured down into said electrode 8 the portion there- 25 of below boss 9 will constitute a well that will retain a small portion of gasolene before it overflows out through perforations 12 and gravitates down into the annular gutter formed by the upper concaved side of 30 head 10 and fills the same.

The upper screw-threaded end of electrode 8 extends above cap 4 and has a cup or basin 16 screwed thereon. This cup or basin comprises a casing 14 the bore in the base of 35 which is in axial alignment with that of electrode 8. The upper end of the bore of the basin is made funnel-shaped to provide a valve-seat 19, and the central portion of said basin has a tubular member 17 extending 40 vertically therefrom that is interiorly threaded and engaged by a needle-valve 18, whose lower tapered end is adapted to engage said funnel-shaped valve-seat 19. Just above the bottom of the basin tubular member 17 has 45 one or more inlet ports 20 therein through which the gasolene can, when the needle-valve has been moved upward, flow from the basin into the electrode.

In operation, needle-valve 18 is turned so 50 as to close the bore of the casing when gasolene is poured into the basin. The said valve is then turned in the opposite direction to open said bore and to permit the gasolene to flow down into the tubular electrode and 55 through the apertures therein into the annular gutter of the head. Any excess of gaso- 60 lene will flow over the edges of the head and into the cylinder. When the valve is moved to close the bore of the electrode and the 65 engine "cranked" the sparks will pass between the edge of head 10 of electrode 8 and electrodes 2 and ignite the gasolene held by said head, at the same time exploding the gaseous vapors within the cylinder. As the

incandescent and the gasolene within the well or lower portion of the bore of electrode 8 will vaporize and be forced down around the annular edge of head 10 and enrich the mixture of gas at the point where 70 the spark occurs and do this for the first four or five hundred explosions after the engine is started at the point where most needed. The explosions in the cylinder below said head are deflected by the convexed 75 underside of the same so that the spent products of explosions will not enter the chamber formed in the lower end of the plug above said head and permit carbon to accumulate therein and close perforations 12 of the tubu- 80 lar electrode, or short circuit said electrode 8 and the walls of the bore of plug 1.

What I claim as new is:—

1. A spark-plug for explosive engines comprising a suitable metallic plug having 85 electrodes connected with and depending from the lower end thereof, a tubular body or barrel of suitable insulating material retained thereby, an axially disposed tubular electrode supported within the bore of 90 said body through which gasolene can be passed, which is closed at its intake end while the engine is in operation the lower end of which extends below the lower end of said plug and has a screw-threaded bore 95 in its lower end, a suitable manually operated closure for the upper end of the bore thereof, a concavo-convex head, and a screw that engages said bore and retains said head on the lower end of said axial electrode. 100

2. A spark-plug for explosive engines comprising a suitable plug, a suitable metallic electrode connected with and depending from its lower annular edge, a tubular body or barrel of insulating material retained 105 thereby, an axially disposed tubular electrode supported within the bore of said body the lower end of which extends below the lower end of the plug and which has a cup or basin supported by the upper end of said 110 axially disposed electrode having a tubular member projecting centrally from the bottom thereof, a needle-valve engaging the screw-threaded bore of said tubular member and engaging a suitable valve-seat in the 115 bottom of said basin for controlling the discharge therefrom into said electrode, and a head having a concaved upper side secured to the lower end of said electrode and closing the bore thereof. 120

3. A spark-plug for explosive engines comprising a suitable plug, a suitable metallic electrode connected with and depending from its lower annular edge, a tubular body or barrel of insulating material retained 125 thereby the lower portion of the bore of which is greater in diameter than that of the upper portion thereof, an axially disposed tubular electrode supported within the bore of said body the lower end of which extends 130

below the lower end of the plug and which has a cup or basin supported by the upper end of said axially disposed electrode having a tubular member projecting centrally from the bottom thereof, a needle-valve engaging the screw-threaded bore of said tubular member and engaging a suitable valve-seat in the bottom of said basin for controlling the discharge therefrom into said electrode, and a head having a concaved upper side secured to the lower end of said electrode and closing the bore thereof.

5 In witness whereof I have hereunto set my hand this 17th day of August, 1916.
